(57) **CLAIM**

The ornamental design for a hanging plant brace, as shown and described.

DESCRIPTION

FIG. 1 is a front perspective view of a hanging plant brace, showing my new design;

FIG. 2 is a right side elevational view thereof, the left side being a mirror image of the right side;

FIG. 3 is a top plan view thereof;

FIG. 4 is a bottom plan view thereof;

FIG. 5 is a front elevational view thereof; and,

FIG. 6 is a rear elevational view thereof.

In FIG. 1 of the drawings, the broken line disclosure of a tree trunk and chain is for illustrative purposes only and forms no part of the claimed design.
